(57) **CLAIM**

The ornamental design for a foldable table, as shown and described.

DESCRIPTION

FIG. 1 is a perspective view of a first embodiment of a foldable table, in a folded configuration;

FIG. 2 is a front view thereof;

FIG. 3 is a rear view thereof;

FIG. 4 is right side view thereof;

FIG. 5 is a left side view thereof;

FIG. 6 is a top plan view thereof;

FIG. 7 is a bottom plan view thereof;

FIG. 8 is a perspective view of the foldable table of FIG. 1, shown in an unfolded configuration;

FIG. 9 is a front view thereof;

FIG. 10 is a rear view thereof;

FIG. 11 is right side view thereof;

FIG. 12 is a left side view thereof;

FIG. 13 is a top plan view thereof;

FIG. 14 is a bottom plan view thereof;

FIG. 15 is a perspective view of a second embodiment of a foldable, in a folded configuration;

FIG. 16 is a left perspective view thereof;

FIG. 17 is a front view thereof;

FIG. 18 is a rear view thereof;

FIG. 19 is right side view thereof;

FIG. 20 is a left side view thereof;

FIG. 21 is a top plan view thereof;

FIG. 22 is a bottom plan view thereof;

FIG. 23 is a perspective view of the foldable table of FIG. 15, shown in an unfolded configuration;

FIG. 24 is a front view thereof;

FIG. 25 is a rear view thereof;

FIG. 26 is right side view thereof;

FIG. 27 is a left side view thereof;

FIG. 28 is a top plan view thereof;

FIG. 29 is a bottom plan view thereof;

FIG. 30 is a perspective view of a third embodiment of a foldable table, in a folded configuration;

FIG. 31 is a front view thereof;

FIG. 32 is a rear view thereof;

FIG. 33 is right side view thereof;

FIG. 34 is a left side view thereof;

FIG. 35 is a top plan view thereof;

FIG. 36 is a bottom plan view thereof;

(Continued)

FIG. 37 is a perspective view of a foldable table of FIG. 30, shown in an unfolded configuration;
FIG. 38 is a front view thereof;
FIG. 39 is a rear view thereof;
FIG. 40 is right side view thereof;
FIG. 41 is a left side view thereof;
FIG. 42 is a top plan view thereof;
FIG. 43 is a bottom plan view thereof;
FIG. 44 is a perspective view of a fourth embodiment of a foldable table, in a folded configuration;
FIG. 45 is a left perspective view thereof;
FIG. 46 is a front view thereof;
FIG. 47 is a rear view thereof;
FIG. 48 is right side view thereof;
FIG. 49 is a left side view thereof;
FIG. 50 is a top plan view thereof;
FIG. 51 is a bottom plan view thereof;
FIG. 52 is a perspective view of a foldable table of FIG. 44, shown in an unfolded configuration;
FIG. 53 is a front view thereof;
FIG. 54 is a rear view thereof;
FIG. 55 is right side view thereof;
FIG. 56 is a left side view thereof;
FIG. 57 is a top plan view thereof; and,
FIG. 58 is a bottom plan view thereof.
